UNITED STATES PATENT OFFICE

BERNARD F. MULDOON, OF MOUNTAIN VIEW, NEW JERSEY, ASSIGNOR TO HENRY HYMAN, OF BROOKLYN, NEW YORK

DESIGN FOR AN ELECTRIC LIGHT SOCKET

Application filed August 24, 1928. Serial No. 27,954. Term of patent 14 years.

To all whom it may concern:

Be it known that I, BERNARD F. MULDOON, a citizen of the United States, residing at Mountain View, county of Passaic, and State of New Jersey, have invented a new, original, and ornamental Design for Electric Light Sockets, of which the following is a specification, reference being had to the accompanying drawing, forming a part thereof,

Fig. 1 is a side view of the device, and Fig. 2 is a perspective view of the same.

I claim:

The ornamental design for an electric light socket, as shown.

BERNARD F. MULDOON.
